UNITED STATES PATENT OFFICE.

EDWIN S. VOTEY, OF DETROIT, MICHIGAN.

DESIGN FOR AN ORGAN-CASE.

SPECIFICATION forming part of Design No. 17,952, dated December 13, 1887.

Application filed August 30, 1887. Serial No. 248,323. Term of patent 7 years.

To all whom it may concern:

Be it known that I, EDWIN S. VOTEY, a citizen of the United States, residing at Detroit, county of Wayne, State of Michigan, have invented a certain new and original Design for Organ-Cases; and I declare the following to be a full, clear, and exact description of the same, reference being had to the accompanying drawing, which forms a part of this specification.

10 The figure is a front elevation of an organ-case embodying my design.

A represents the top board of the organ proper and the portion opposite.

15 B represents the usual space beneath the keyboard. I complete the upper portion above the top board, A, in a unique cabinet form, as follows:

20 A' is a back which rises in continuation of the plane of the back of the organ. It has a circular field, A², formed upon it, which may be either defined by a circular molding, a², or the circular field may be built out so as to stand somewhat in front of the face of the back A'. The interior of the circle may either be plain or 25 veneered, or it may be provided with a mirror.

20 C is the top, which projects forward to the front of the organ-case. Uprights C' are interposed between this top and the top board, A, of the organ proper.

30 C² represents shelves which extend from front to rear, and C³ represents a curved rail with posts c, which is in the general plane of the front of the organ, so as to leave a space back of it on the top board, A, between this front rail, C, and the back A'.

35 C' is a bracket adjacent to the front of the organ. C⁶ is a rail at the front of the organ, and which is extended to the rear across the ends back of the uprights C'.

B' represents the bottom panels at the base 40 of the organ-case, which panels are curved so that at the top they will project out near to the front of the organ, so as to occupy this usually vacant space.

45 My design in this respect comprehends two features: first, the curved fronts or panels, and second, the curved fronts or panels provided with ornamentation in the form of one or more branches or vines, substantially as shown in the drawing. 50

What I claim is—

1. In the design for an organ-case, the upper portion thereof, as shown, consisting of the circular field A², the curved rail C³, post c, cabinet shelves C², arranged on each side of the 55 circular field, and the rail C⁶, arranged above the circular field and shelves, substantially as set forth.

2. In the design for an organ-case, the lower portion thereof, as shown, consisting of the 60 panels B', arranged upon each side of the front and having an inward and downward curve, said panels being ornamented by vines or branches, substantially as set forth.

3. The design for an organ-case herein shown, 65 the same consisting of a circular field, A², curved rail and posts C³ c, cabinet shelves C² on each side, rail C⁶, sides C', and the curved panels B, the latter being arranged below the manual and the former above, substantially as 70 set forth.

In testimony whereof I sign this specification in the presence of two witnesses.

EDWIN S. VOTEY.
